PARING AND CORING TOOL

Myron J. Zimmer, Chicago, Ill., assignor to The
Edward Katzinger Company, Chicago, Ill., a
corporation of Illinois

Application October 19, 1938, Serial No. 235,886

7 Claims. (Cl. 30—279)

This invention relates to a tool for paring and coring fruits and vegetables, having a blade movably connected with a handle and adapted to swing automatically in substantial alignment with the line of engagement desired for uniformly peeling an article of irregular contour and being capable of such movement without wrist-turning action on the part of the operator.

It is an object of this invention to provide a device of this character that is inexpensive to manufacture yet is durable and of pleasing design.

With the above and other objects in view, as will be apparent, this invention consists in the construction, combination and arrangement of parts, all as hereinafter more fully described, claimed and illustrated in the accompanying drawing, wherein:

Fig. 1 is a side elevation of a paring and coring tool constructed according to the present invention.

Fig. 2 is a plan view showing a flat blank or sheet stamped to form a blade and handle extension in accordance with this invention.

Fig. 3 shows the blank of Fig. 2 in side elevation and bent to final form as contemplated by this invention.

Fig. 4 is a plan view showing a flat blank stamped preliminary to forming a sleeve for receiving and engaging the extension of the blade aforesaid within a suitable handle.

Fig. 5 is a side elevational view showing the sleeve of Fig. 4 in final form.

Fig. 6 is an enlarged transverse section taken on line 6—6 of Fig. 1.

Fig. 7 is an enlarged transverse section taken on line 7—7 of Fig. 1.

Fig. 8 is a fragmentary side elevational view of a modified form of handle extension.

Fig. 9 is a plan view of a modified form of sleeve for cooperation with the type of extension shown in Fig. 8.

Fig. 10 is an enlarged end view of the handle extension and sleeve assembly embodying the features of the elements shown in Figs. 8 and 9.

Referring first to the structure illustrated in Figs. 1 to 3, inclusive, the numeral 10 indicates a blade having parallel side edges 11 and 12, and an end extension 13 which, when bent, will form a tubular structure or journal. The blade 10 and extension 13 are preferably formed from an integral blank of sheet metal or the like with the sides of the blank recessed as at 14 to provide a relatively narrow shank or neck portion inter-

mediate the blade portion 10 and the extension 13. To complete the formation of the blade, a slot 16 is cut lengthwise of the edges 11 and 12 of the blade and is disposed centrally thereof, to define edges 17 and 18 which are preferably sharpened to provide cutting edges as contemplated by this invention wherein either of said edges coacts with the other as a guard in leading relation to cutting edge during operation of the blade. In order to dispose the cutting edges 17 and 18 of the blade 10 in operative relation to the surface of an article to be cut or pared thereby, the edges 11 and 12 of the blade are bent inwardly toward each other to create a transversely arched blade structure. The shank portion 15 is also bent as at 20 in Fig. 1 to align the cutting edges 17 and 18 with the longitudinal axis of the extension 13.

Referring now to Figs. 4 and 5, as well as Fig. 1, the numeral 21 indicates a flat blank of metal stamped to form parallel edges which, when bent, will form a tubular sleeve or bearing within which the extension 13 of the blade 10 may freely turn. The sleeve 21 is adapted to be seated in the central bore 22 of a handle 23 of suitable design and construction. A ferrule 24 of desired shape and style may be fastened to the forward end of the handle and through which the extension 13 of the blade 10 must pass to enter the handle. To aid in holding the sleeve 21 firmly in the body of the handle 23 defined by the limits of the bore 22, a barb 25 is preferably formed integrally with the sleeve 21. Thus when the sleeve 21 is driven into the bore 22 of the handle, the point thereof projecting toward the blade 10 will be in a position to embed itself in the handle under any influence tending to withdraw the sleeve 21 therefrom.

In order to prevent longitudinal movement of the blade 10 with reference to the handle, and also to limit rotation of the blade 10 within predetermined limits of movement consistent with efficient paring or peeling action of the cutting edges 17 and 18, an ear or lug 26 is struck inwardly from the body of the sleeve 21 for reception in a transverse slot 27 cut in the body of the extension 13. As shown in Fig. 6, the end edges of the lug 26 thus serve as stops against which the edges of the slot 27 parallel to the length of the extension 13 may be engaged to limit for and aft movement of the blade relative to the handle.

Figs. 8, 9 and 10 illustrate an extension on the blade corresponding to the journal 13 of Figs. 2 and 3, and a sleeve corresponding to the

sleeve 21 of Figs. 4 and 5, with slight modifications in construction. In this form of the invention, an outwardly extending ear or lug 28 is formed at the trailing or inner end of a sleeve 29 which is adapted to engage the parallel edges of a notch 30 cut from the corresponding end of a sleeve 31. The lug 28, as will be observed, overhangs the rear transverse edge of the notch 30, being thereby effective to prevent outward longitudinal movement of the blade with reference to the handle.

It will be understood that changes may be made in details of construction and arrangement of parts without departing from the spirit and scope of this invention. Accordingly, this invention is not limited to the exact structure or structures shown and described hereinbefore, except as defined by the appended claims.

What is claimed is:

1. In a paring tool, a handle, a blade comprising a sheet metal blank stamped to create a transversely arched body and a tubular extension projecting longitudinally from one end thereof, means providing a cutting edge and a guard edge in spaced relation thereto including a sharp edged slot extending centrally and longitudinally of the outer side edges of said blade, means for engaging and mounting said blade for pivotal movement of the cutting edge relative to said handle about an axis concentric with the longitudinal axis of said handle including a sleeve extending axially inwardly from the toolward end of said handle adapted to cooperate with said tubular extension, and a transverse slot in said extension presenting stops for engaging a member projecting inwardly from the body of said sleeve to limit axial and pivotal movement of said tubular extension relative to said sleeve.

2. In a paring tool, a handle, a blade comprising a sheet metal blank stamped to create a transversely arched body and a tubular extension projecting longitudinally from one end thereof, means providing a cutting edge and a guard edge in spaced relation thereto including a sharp edged slot extending centrally and longitudinally of the outer side edges of said blade, means for engaging and mounting said

blade for pivotal movement of the cutting edge relative to said handle about an axis concentric with the longitudinal axis of said handle including a sleeve extending axially inwardly from

5 the toolward end of said handle adapted to cooperate with said tubular extension, and a transverse slot in said extension presenting stops for engaging a member projecting inwardly from the body of said sleeve to limit axial movement 10 of said tubular extension relative to said sleeve.

3. In a paring tool as described in claim 2, means for engaging and mounting said sleeve against axial movement relative to said handle.

4. In a paring tool as described in claim 2 15 means for engaging and mounting said sleeve against axial movement relative to said handle including a barb extending outwardly from said sleeve.

5. In a paring tool, a handle having a central 20 bore extending axially inwardly from the toolward end thereof, a sleeve seated in said bore, a blade having a shank extending longitudinally from one end thereof journaled in said sleeve, and interlocking means on said shank and sleeve 25 for limiting axial and pivotal movement of the shank in said sleeve.

6. In a paring tool, a handle having a central bore extending axially inwardly from the toolward end thereof, a sleeve seated in said bore, 30 a blade having a shank extending longitudinally from one end thereof journaled in said sleeve, and means for limiting axial and pivotal movement of the shank in said sleeve including a transverse slot in said shank presenting stops 35 for engaging a member projecting inwardly from the body of said sleeve.

7. In a paring tool, a handle having a central bore extending axially inwardly from the toolward end thereof, a sleeve seated in said bore, 40 a blade having a shank extending longitudinally from one end thereof journaled in said sleeve, and means for limiting axial and pivotal movement of said shank in said sleeve including a recess in said sleeve presenting stops for engaging a member projecting outwardly from the 45 body of said shank.
